UNITED STATES PATENT OFFICE.

EDWARD W. TRAUTMAN, OF LONG BEACH, MISSISSIPPI.

TOY.

1,351,075.

Specification of Letters Patent. Patented Aug. 31, 1920.

Application filed October 22, 1919. Serial No. 332,375.

To all whom it may concern:

Be it known that I, EDWARD WILLIAM TRAUTMAN, a citizen of the United States, and a resident of Long Beach, in the county 5 of Harrison and State of Mississippi, have invented certain new and useful Improvements in Toys, of which the following is a specification.

My invention is an improvement in toys, 10 and has for its object to provide a device of the character specified wherein the toy has the outline of a vessel, as, for instance, an aeroplane, torpedo, ship or the like, and is provided with a supporting pulley adapted 15 to run upon a cord to which the toy is swiveled, the toy having guiding vanes and a propeller, and having means for exploding a torpedo when it strikes an obstruction.

In the drawings:

20 Figure 1 shows the improved toy in use; Fig. 2 is an enlarged side view of the toy; Fig. 3 is a section on the line 3—3 of Fig. 2;

25 Fig. 4 is a partial longitudinal section at the front end of the toy.

In the present embodiment of the invention the improved toy is shaped to simulate an aerial vessel, comprising a body 1 which may be of wood or the like, or which may be 30 hollow and of light metal, vertical and horizontal rudders 2 and 3 at the rear of the body, and a centerboard 4.

At the front of the centerboard there is 35 arranged a propeller 5, the said propeller being adapted to be driven by the air as the toy is propelled through the air. The toy is adapted to be suspended from a cord indicated at 6, by means of a pulley 7 which is journaled in a casing or stirrup 8 adapted 40 to engage over the cord 6.

The stirrup is connected to the body of the toy by means of a double swivel indicated at 9, and, preferably, the body is provided at its front end with means for exploding a torpedo, as, for instance, the paper caps used in toy pistols. For this purpose the body has a slot or passage 10 extending inwardly from the side and top, and adapted 45 to receive a paper cap indicated at 11.

50 A firing pin 12 extends from the recess forwardly, beyond the front end of the body, and this firing pin is normally held in outward position by a spring 13 which encircles the pin between the firing head 14 thereof and the body. The firing head 14 which limits the outward movement of the firing pin under the influence of the spring nor-

mally rests against the cap, when the cap is in the recess, and it will be obvious that when the forward end of the firing pin 60 strikes an obstruction the cap will be exploded.

In use, the cord 6 is supported at one end by a fixed object, as, for instance, a post 15, and the other end is held in the hand of the operator. The pulley 7 is placed upon the cord, and by means of the hand the operator propels the toy along the cord. The body has sufficient weight to cause it to be driven easily under the impulse of the 70 operator's hand, and the toy will move smoothly and swiftly toward the post. As it strikes the post the cap will be exploded and the force of the impact will swing the device into reverse position, so that now the 75 propeller faces in the opposite direction. By lowering that end of the cord which is held in the hand, the toy will be constrained to run back along the cord to the operator's hand. The force of the rebound will cause 80 the toy to move for a considerable distance.

It will be obvious that the toy might be arranged to represent any kind of a vehicle, or it might be arranged to carry small objects, which would be released by the force 85 of the impact, as, for instance, hot rivets. On the return trip of the toy its progress may be regulated by raising and lowering the string, as indicated in Fig. 1.

I claim:

1. A toy of the character specified comprising a vessel having guiding planes, a pulley connected with the vessel and adapted to run upon a cord connected at one end to a fixed object, a double swivel connection 95 between the pulley and the vessel, said vessel having means for exploding a torpedo or cap by contact of the toy with the fixed object.

2. A toy of the character specified comprising a vessel having guiding planes, a pulley connected with the vessel and adapted to run upon a cord connected at one end to a fixed object, said vessel having means for exploding a torpedo or cap by contact 105 of the toy with the fixed object.

3. A toy of the character specified, comprising a vessel, a pulley connected therewith and adapted to run down a cord supported at one end by a fixed support, said 110 vessel having means for exploding a torpedo or cap by contact of the toy with a fixed object.

EDWARD W. TRAUTMAN.
